SOLDERLESS TERMINAL BLOCK FOR WIRE BANKS

Frank R. Edgerton, Los Angeles, Calif., assignor to General Dynamics Corporation, Rochester, N.Y., a corporation of Delaware

Application May 7, 1957, Serial No. 657,527

4 Claims. (Cl. 339—66)

My invention relates to terminal blocks in general and more particularly to terminal blocks for establishing connections between substantially rigid, closely spaced conductors, such as are found in wire bank assemblies used for certain types of telephone switching apparatus, with other conductors, such as those contained in a connecting cable.

My invention may be used in connection with wire bank multiple formed in the manner set forth in U.S. Patent 2,506,730 to F. A. Morris. Such multiple is usually formed from sections or assemblies comprising two parallel rows of substantially rigid, round, uninsulated conductors maintained in spaced relationship to each other along the length of the conductors. Heretofore it has been the practice to establish connections between each of the multiple conductors and individual, insulated wires (usually contained in a cable) by introducing the opposite ends of a sleeve over the individual cable wire and bank conductor and thereafter soldering the sleeve in place. The exposed portions of the insulated wire and the sleeve may be covered with so-called spaghetti insulation in order to prevent shorts between adjacent ones of the sleeves. The use of such sleeve connectors offers several disadvantages including the necessity for making individual soldered connections on each wire bank conductor, the possibility of dropping solder into the wire bank, and the possibility of inadvertently burning the spaghetti sleeves in the course of soldering other connections.

Accordingly, it is an object of my invention to provide a new and improved terminal block for electrically joining conductors.

Another object of my invention is to provide a new and improved solderless connector block for electrically joining conductors.

Another object of my invention is to provide a new and improved terminal block for use with bare wire bank multiple.

Another object of my invention is to provide a new and improved connector block for use with wire bank multiple which depends upon mechanical distortion of the conductors to establish reliable electrical connections.

Another object of my invention is to provide a new and improved solderless connector block for wire bank multiple made up of sections comprising two parallel rows of conductors.

For a better understanding of my invention, reference is made in the following description to the drawing attached to and forming a part of the present specification, and in which:

Figs. 1a, 1b and 1c show a top plan view of a terminal block, a side elevation of a terminal block in place on a wire bank subassembly, and a bottom plan view of the wire bank subassembly, respectively;

Fig. 2 shows a section taken through section 2—2 indicated in Fig. 1a; and,

Fig. 3 shows a section taken through section 3—3 indicated in Fig. 2.

Referring to the drawings, Fig. 1b shows the side ele-

vation of the end portion of a wire bank section. As indicated in Fig. 1c, the section comprises first and second pluralities of substantially straight, round rods or conductors 5a and 5b arranged in first and second rows, respectively. The conductors in each row are evenly spaced apart from and parallel to each other; similarly, the rows are parallel to each other. The section elements are held in place by a plurality of insulator blocks 10 spaced apart from each other along the length of the section. The lengths of conductors 5a and 5b extending upwardly from the topmost block 10 are substantially equal.

A terminal block 1 of insulating material comprising web portion 3 connecting lower flange portion 4 to upper flange portion 2 is provided for the ultimate purpose of individually connecting each one of conductors 5a and 5b to one of a plurality of insulated flexible conductors such as the one comprising wire 8 and insulating material 9. Accordingly, the end of each of conductors 5a and 5b is introduced into a corresponding one of first and second rows of parallel bores which pass through flange 4 from top to bottom. Each bore is close fitting to the received one of rods 5a and 5b; the bores are evenly spaced apart from each other by the same distance as the distance separating adjacent ones of conductors 5a and 5b.

Referring to Figs. 2 and 3, the rows of bores are positioned to admit a certain portion of that part of each of conductors 5a and 5b which lies between flanges 2 and 4 to the left- and right-hand channel, respectively, formed in the sides of block 1 by both flanges and the web. The remaining portion of that part of each conductor in the first and second rows lying between flanges 2 and 4 is received within one of a series of depressions or flutes formed in left- and right-hand sides of web 3. Each of these depressions lies immediately over each one of the bores, each depression being located in web 3 so that its surface is continuous with the surface of the corresponding bore. The depressions extend the full width of web 3 and terminate in surfaces which are substantially level with the inner surface of flange 2. After the ends of conductors 5a and 5b have been introduced to the bores in flange 4, block 1 is advanced downwardly in a direction parallel to the length of conductors 5a and 5b until the rods encounter the inner surface of upper flange 2.

In order to connect each of insulated wires 8 with the corresponding one of rods 5a and 5b, each insulated wire 8 is electrically connected to a cylindrical sleeve connector 6 by any of a number of commercially available fastened devices such as tapered plug 11. Each sleeve 6 is introduced through one of a pair of rows of openings in flange 2 as indicated in Figs. 2 and 3 and advanced in the direction of flange 4. Each opening fits closely around the received one of connectors 6. The rows of openings in flange 2 are substantially parallel to the bores 55 passing through flange 4 and are positioned so that each of pins 7 which extend concentrically from each of sleeve 6 intersects the end of the one of rods 5a and 5b received within the corresponding bore at a point on the rod which faces away from web 3. Each sleeve 6 is then further advanced in the direction of flange 4 so that its attached pin 7 and the engaged one of rods 5a and 5b are mechanically distorted by scoring each other. The scoring action is effective to establish a low resistance contact between each of rods 5a and 5b and the corresponding one of wires 8.

Corresponding bores in each of the first and second rows are centered on the same line which is also perpendicular to flange 3. For this reason the corresponding wire-receiving depressions in opposite sides of web 3 are similarly situated. When corresponding ones of conductors 5a and 5b in the first and second conductor rows are laterally displaced against opposite sides of web

3 by the introduction of connectors 6 into the flange 2 openings, the lateral distortions of opposite ones of rods 5a and 5b against web 3 are substantially equal and opposite because all rods and pins are substantially matched in size, shape and material. Under these conditions, the thickness of web 3 can be determined on the basis of factors other than the resistance of the insulating material in block 1 to distortion. Because each of rods 5a and 5b is compressed between one of pins 7 and flange 3, no rotational force is exerted by conductors 5a and 5b on flange 4. Therefore, the thickness and width of flange 4 also may be determined on the basis of factors other than the resistance of the insulating material in block 1 to tensile and shearing forces.

While I have shown and described a specific embodiment of my invention, other modifications will readily occur to those skilled in the art. I do not, therefore, desire my invention to be limited to the specific arrangement shown and described, and I intend in the appended claims to cover all modifications falling within the spirit and scope of my invention.

What I claim is:

1. In a device for making an electrical connection between a metallic rod and a pin-bearing connector, a block of insulating material comprising upper and lower flanges having opposed, inward-facing surfaces connected by a web, a bore passing through said lower flange in the direction of said upper flange and underlying a part of said web, a depression formed in said web overlying said bore, the end of said rod being introduced through said bore and extending to the inward-facing surface of said upper flange, a portion of said rod being received within said depression, an opening passing through said upper flange in the direction of said lower flange for receiving said connector, said bore and said rod therein being oriented with respect to said opening for making said pin engage said rod at a point on said rod facing away from said web as said connector is advanced in the direction of said lower flange, whereby the end of said rod is located relative to said connector and said block as said pin and said rod are brought into electrical contact and the mechanical displacement of the end of said rod lying between said flanges is limited to the confines of said depression.

2. In a device for making an electrical connection between a metallic rod and a pin-bearing connector, a block of insulating material comprising upper and lower flanges having opposed, inward-facing surfaces connected by a web, a bore passing through said lower flange in the direction of said upper flange and underlying a portion of said web for receiving the end of said rod, a depression formed in and extending to said inner surface of said upper flange in said web and overlying said bore for receiving a portion of said rod as said rod is advanced in the direction of said inward-facing surface of said upper flange, an opening passing through said upper flange in the

5 direction of said lower flange for receiving said connector, said bore and said rod therein being oriented with respect to said opening for making said pin engage said rod at a point on said rod facing away from said web as said connector is advanced through said opening in the direction of said lower flange, whereby the end of said rod is located relative to said block and the mechanical displacement of said rod is limited to the confines of said depression.

10 3. In a device for individually connecting each of first and second rows of parallel rods to corresponding ones of first and second pluralities of pin-bearing sleeve connectors, a block of insulating material comprising upper and lower flanges having opposed, inward-facing surfaces connected by a web, each of said flanges having portions projecting from both sides of said web, first and second rows of bores passing through said lower flange in the direction of said upper flange on opposite sides of said web for receiving the ends of said rods in said first and 15 said second rows, respectively, corresponding bores in said first and said second rows being located at opposing points on the sides of said web, portions of each of said bores underlying said web, depressions formed in the surfaces of said web over each of said bores for receiving a portion of the one of said rods as the ends of said rods are advanced in the direction of said upper flange, first and second rows of openings passing through said upper flange in the direction of said lower flange and on opposite sides of said web for receiving said connectors of said first and said 20 second pluralities, respectively, each of said bores and the one of said rods received therein being oriented with respect to the corresponding one of said openings for making said pin of said connector received therein engage the received one of said rods at a point facing away from said web, whereby the mechanical displacement of each of said rods is limited to the confines of the corresponding one of said depressions as each of said connectors is advanced through its opening in the direction of said lower flange, and strain against said web caused by mechanical distortion of corresponding ones of said rods in said first and said second rows is balanced at points distributed along the length of said web.

25 4. The device set forth in claim 3 wherein said depressions extend to said inner surface of said upper flange and the end of each of said rods is extended to said inner surface of said upper flange, whereby the ends of said rods are located relative to said block.
